UNITED STATES PATENT OFFICE.

HENRY HORAN, OF EAST ORANGE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 12,185, dated March 15, 1881.

Application filed February 7, 1881. Term of patent 3½ years.

To all whom it may concern:

Be it known that I, HENRY HORAN, of East Orange, in the county of Essex and State of New Jersey, have invented a new and original 5 Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

A is a group composed of the figure H, containing roses, with circular flowers between them, supported on spreading leaves and surrounded by the projecting branch a, bearing rose-buds, and by the branching ferns b e f.

B is a figure somewhat resembling the group A, and having a center of roses, circular flowers, and leaves surrounded by branching ferns, buds, and leaves.

I is a figure consisting of foliage and of circular flowers resting upon a trellis-work, h, by which it is connected to the figure B. This 25 trellis-work h is rectangular and runs regularly through the whole design, appearing in connection with the various groups and figures.

The figure C is made up of a center of circular flowers, from which branch off leaves and fern-like sprays, and rests on the trellis h.

The figure G is composed of a branch bearing star-flowers and leaves surrounded by branching ferns and resting on a portion of the trellis h, by which it is connected with the 35 figure D, consisting of a center of circular flowers surrounded by leaves branching therefrom, and ferns, and with a spray of roses projecting.

The figure K consists of leaves and flowers growing over a portion of the trellis h.

The figure E consists of circular flowers, 40 leaves, and buds, supported by a portion of the trellis h, a projection of which connects the figures E and B.

The effect of the design is that of a rectangular disconnected trellis-work supporting or 45 connecting the various figures described.

I claim—

1. The design for a carpet, consisting of the figure H, substantially as shown.
2. The design for a carpet, consisting of the 50 group A, composed of figures H, a, b, e, and f, substantially as shown.
3. The design for a carpet, consisting of the figure I, substantially as shown.
4. The design for a carpet, consisting of the 55 figure D, substantially as shown.
5. The design for a carpet, consisting of the figure K, substantially as shown.
6. The design for a carpet, consisting of the 60 figure E, substantially as shown.
7. The design for a carpet, consisting of the figure G, substantially as shown.
8. The design for a carpet, consisting of the figure C, substantially as shown.
9. The design for a carpet, consisting of the 65 figure B, substantially as shown.

10. The design for a carpet, consisting of the trellis-like figure h, substantially as shown.

11. The design for a carpet, consisting of the figures H a b e f I D K E G C B and figures h, 70 substantially as shown.

HENRY HORAN.
